Franz Pfaff Inventor,

By Robert S. Carr,

Attorney.

UNITED STATES PATENT OFFICE.

FRANZ PFAFF, OF ALTWASSER, GERMANY, ASSIGNOR TO THE TRENLE CHINA COMPANY, OF EAST LIVERPOOL, OHIO.

DESIGN FOR A PLATE.

44,586.

Specification for Design.

Patented Aug. 26, 1913.

Application filed June 4, 1913. Serial No. 771,775. Term of patent 3½ years.

To all whom it may concern:

Be it known that I, FRANZ PFAFF, a citizen of Germany, residing at Altwasser, Germany, have invented a new, original, and ornamental Design for Plates, of which the following is a specification, reference being had to the accompanying drawing, forming part thereof.

The figure is a plan view of a plate, showing my new design.

I claim:

The ornamental design for a plate, as shown.

FRANZ PFAFF.

Witnesses:

FELIX GRANTHAM,
ERNST KELLY.
